LEOPOLD RADO, OF BERLIN-HAENSEE, GERMANY

COLLAPSIBLE TUBE OR CONTAINER FOR PASTES AND THE LIKE

Application filed November 28, 1928, Serial No. 322,463, and in Germany May 23, 1928.

This invention relates to a collapsible tube or container for pastes and the like and consists substantially in the tube sleeve being constituted by metal foil, more particularly aluminium foil, covered on the inside of the sleeve or on both sides with cellulose foil, one end of the tube sleeve being provided with a head carrying the screw closing device, and the other end with a closing device.

Up to now, there have been used for the manufacture of such tubes, exclusively metals such as tin, zinc, aluminium and the like. In choosing the material, a manufacturer was always tied to very narrow limits by consideration of the chemical properties of the articles to be packed (foodstuffs, cosmetic and pharmaceutical preparations, paints and the like). The material used was mostly tin as it is least affected by chemical action. Owing however to the high price of these materials, the cost of the tube, and therefore of the articles is greatly increased. A further disadvantage of known tubes is that the thickness of walls of the tube sleeves has to be made very small in view of the flexibility and pliability of the walls, required for squeezing out the paste, so that with the material hitherto used, the tube does not offer sufficient resistances to the mechanical stresses occurring, more particularly to tensional and bending stresses.

If however metal foil, more particularly aluminium foil, coated on the inside of the sleeve or on both sides with cellulose foil, is used for the manufacture of the sleeve-shaped parts of the tube, tubes will be obtained in which all the above mentioned disadvantages are eliminated.

By cellulose foils are meant here the known cellulose hydrate foils, called also cellulose glass skin, cellulose skin or simply cellulose, which are extensively used for the packing of articles of all kinds, for the coating of surfaces, etc., as well as any similar products which are prepared from cellulose derivatives, cellulose ester solutions, cellulose acetate or the like, in the form of foils, skins, films or the like. These cellulose foils are free of fibres and may be used for the purposes of the present invention in combination with

thin metal foils, more particularly with aluminium foil, that is to say the said cellulose foils are secured to the metal foils by means of suitable, preferably transparent, adhesives, such as gelatine solution, vegetable glue, joiner's glue, celluloid solution and varnishes (for instance colophony varnish).

For the manufacture of the hollow bodies are used foils of exceedingly small thickness—cellulose foils of a thickness of about 0.01 mm. and metal foils, more particularly aluminium foil, of a thickness of about 0.008—0.010 mm.

In order to render the cellulose foils in as far as required non-sensitive to the action of moisture, they are coated, before or after their working, in a manner known in itself, with water-repelling substances, such as for instance, cellulose nitrate solution, or celluloid solution which, after they have solidified, leave behind a cohesive layer non-sensitive to water.

The manufacture of the sleeve-shaped part of the tube from the above mentioned combined foils may be done in various ways. For instance, a thicker foil may be used, or two or more foils may be first joined together by an adhesive, and this web of material formed into a tube, the edges being then stuck together.

In this kind of manufacture, there of course always remains visible a seam or joint, and there is always the risk that the tube will burst at the seam. These disadvantages are however completely eliminated by making the tube sleeve in such a manner that the foils are wound in several layers on a suitable former, and the single layers joined together by means of suitable adhesives. Owing to the small thickness of the foils used, the intersection of the single layers, after the winding, will be scarcely visible, and in that way a tube sleeve is obtained which has altogether the appearance of a body made of a single piece, and has an exceedingly high resistance to any mechanical stresses.

The manufacture of a wound or rolled up tube is carried out, for instance, by winding the combined metal-cellulose foils on a cylindrical former of any desired length, with the

application of an exceedingly thin layer of adhesive. In order to ensure as uniform application of the glue as possible, it is advisable to apply the adhesive to the foils during the process of winding, by means of a sprayer nozzle. In that way, tubes of any length can be wound, which afterwards are cut to sleeves of the desired length.

A particular advantage of the tubes according to the invention consists in that they are suitable to be provided in a very simple and effective manner with the "make-up" required for the sale of goods. Thus, for instance, either cellulose foil, or the metal foil, or even the foils already combined may be coloured, printed, embossed or the like in any desired manner. The sleeve of the finished tube may be of course subsequently provided with patterns by embossing it by means of suitable devices. Between the cellulose and the metal foil may also be mounted labels or the like, so that the finished tube will show the label in question at the desired place. Of course, pattern and other effects of various kinds may also be produced in other ways.

If for the manufacture of the tube are used cellulose-metal foils in which the metal foil is provided at previously determined points with recesses, a tube will be obtained with a window constituted by transparent cellulose foils, which shows the contents of the tube.

For the purpose of more fully explaining the invention, the accompanying drawing shows by way of example, a construction of the tube in which the sleeve is constituted by a hollow body wound from a combined cellulose-aluminium foil.

When metal foils are used which are covered with cellulose foils only on one side, the winding or rolling up, is preferably effected so that the cellulose foil is positioned on the inside. As the cellulose foil, more particularly the cellulose foil provided with a coating of water-repelling substances, is not affected by chemical action, there is no restriction as regards the choice of the metal. Metals may therefore be used which are in themselves corroded by the contents of the tube.

Owing to the cellulose covering, the metal foil is given an exceedingly great strength, more particularly great resistance to the great tensional stresses which chiefly occur when the tube is used.

By using metal foils covered with cellulose on both sides, not only the tensile strength of the metal foil is increased by the tensile strength of the second cellulose foil, but in addition any possibility of destruction of the metal foil by crushing or mechanical injury is eliminated. In such a case, the metal foil may be made as thin as desired. Although in this way a thickness of the tube wall is obtained, which is substantially less

than that hitherto required, the tube, in addition to its greater flexibility and pliability, has an incomparably greater durability than that of the tubes made of tin or the like.

The attached drawing shows an elevation, partly in section, of a preferred modification of my novel tube.

In the tube shown in the drawing, the sleeve-shaped part *a* is wound from a metal foil covered with cellulose foils on both sides. In the drawing is shown in the cross section of the wall only one such layer which is constituted by metal foil, for instance aluminium foil *b*, and two cellulose foils *c* and *d*.

The layer *d* which is in contact with the tube contents, and if necessary also the outer layer *c*, is provided with a coating, not shown in the drawing, of cellulose nitrate solution, celluloid solution or the like, for the purpose of eliminating its hygroscopic properties. The tube sleeve is compressed at the bottom end and closed by a metal clip *e*. The head *h* carrying the screw closing device *f*, *g*, is connected to the sleeve-shaped part in such a manner that the upper edge of the latter is folded and flanged over inwardly and clamped to the head *h* by means of a clamping plate *i*. For the purpose of preventing the sleeve edge from slipping out, the head *h* may be provided with a circular groove, and the clamping plate *i* with a corresponding bead or projection. The securing of the head *h* to the sleeve *a* may also be effected in some other manner, for instance by flanging over the edges of the sleeve and of the head. The outermost transparent layer *c* may be coloured on the inner face, or the metal foil *b* on the outer face, and provided with inscriptions or labels, so that the latter are protected from any damage.

The tube described in the foregoing is more particularly suitable on account of its great tensile strength, for such fillings in which there is a strong mechanical stress on the tube during use.

The tube according to the invention is distinguished by its great durability and strength and may be provided in a simple and very effective manner with any desired make-up required for the sale of goods.

I claim:

A collapsible tube comprising a body portion permanently sealed at its lower extremity and sealed at its upper extremity by a removable cap, the said body portion comprising aluminum foil lined with fibreless cellulose hydrate and a water-impervious film adherent to the cellulose hydrate on the inner surface of the said body portion.

In testimony whereof I affix my signature.

LEOPOLD RADO.
